UNITED STATES PATENT OFFICE.

FREDERICK K. STONE AND FRANK P. STONE, OF CHICAGO, ILLINOIS.

DESIGN FOR A VEHICLE-BODY.

No. 38,621.

Specification for Design.

Patented June 11, 1907.

Application filed December 31, 1906. Serial No. 350,700. Term of patent 14 years.

To all whom it may concern:

Be it known that we, FREDERICK K. STONE and FRANK P. STONE, citizens of the United States, residing at Chicago, in the county of Cook and State of Illinois, have invented a new, original, and ornamental Design for a Vehicle-Body, of which the following is a specification, reference being had to the accompanying drawing, forming a part hereof.

The invention consists in the ornamental design for a vehicle body, as shown in the accompanying drawing in which

Figure 1 is a view in perspective; and Fig. 2 is a view in side elevation of a vehicle body embodying my new design.

I claim:

The ornamental design for a vehicle body as shown.

FREDERICK K. STONE.
FRANK P. STONE.
